AUTOMOTIVE VEHICLE

James L. Darden, Ferndale, Mich., assignor to Stude-baker-Packard Corporation, Detroit, Mich., a corporation of Michigan

Application January 31, 1955, Serial No. 34,290

Term of patent 14 years

(Cl. D14—3)

FIG. 3

Figure 1 is a left rear perspective view of an automotive vehicle showing my new design;

Figure 2 is a right rear perspective view; and

Figure 3 is a left side elevational view thereof.

The dominant features of my design reside in the full line portion of the drawings.

I claim:

The ornamental design for an automotive vehicle or similar article, substantially as shown and described.
